UNITED STATES PATENT OFFICE.

HIRAM BARBER, OF CHICAGO, ILLINOIS.

SPRING DRAFT ATTACHMENT FOR VEHICLES.

SPECIFICATION forming part of Letters Patent No. 415,318, dated November 19, 1889.

Application filed December 8, 1888. Serial No. 292,983. (No model.)

To all whom it may concern:

Be it known that I, HIRAM BARBER, a citizen of the United States, residing at Chicago, in the county of Cook and State of Illinois, have 5 invented a certain new and useful Improvement in Spring Draft Attachments and Tongue-Supports for use on Wagons and other Vehicles, of which the following is a full, clear, concise, and exact description, reference being had to the accompanying drawings, forming a part of this specification.

The object of my invention is, first, to secure a yielding connection between the evener and the fixed point of draft upon a wagon or 15 other vehicle; secondly, to secure at the same time a satisfactory support of the tongue of the vehicle against the downward pressure and thrust thereof upon the neck of the draft-animal.

20 In spring draft attachments heretofore in use it has been found difficult to secure the ready removal of the evener for detached use. In tongue-supports heretofore in use one great obstacle to overcome has been to find a 25 point of attachment at the rear part of the tongue of the vehicle without interfering with the method of fastening the evener by means of the old-fashioned bolt and hammer-strap.

In the invention herein described I have 30 sought to secure both of these objects by means of one device.

In the drawings, Figure 1 is a side elevation of my improved spring draft attachment and tongue-support. Fig. 2 is a sectional view of 35 my spring draft attachment and tongue-support, taken on the line 3 3 of Fig. 3. Fig. 3 is a plan view of my improved draft-equalizer and support. Fig. 4 is a sectional view taken on the line 2 2, Fig. 2; Fig. 5, a detail view of 40 a section of the evener with plate and sleeve, through which the evener-bolt passes; Fig. 6, a perspective view of the bolt T, which holds head-block H in place. Fig. 7 is a perspective view of the clevis M, in which the evener 45 is held and works; Fig. 8, a transverse section on the line 1 1, Fig. 2.

In construction the exterior frame of my spring draft attachment and tongue-support is composed of the plate P, the casings C and 50 D, and the bar B. The casings C and D are attached firmly to the front and rear ends, re-

spectively, of the plate P. The casing C is open at the rear end thereof and the casing D at the forward end. The plate P is provided with a central longitudinal slot o, extending from the rear end of the casing C back to the casing D. The head-block H is provided with the shank k and the head d, the forward face of which is plain and provided with the shank k, projecting from the center 55 thereof and at right angles thereto, and has its rear face convex. The head d is also provided with a perpendicular aperture h for the passage of the stem e of the bolt T, the lower end of which enters the block X. The lower section of the block X lies below the plate P, and is of greater width than the slot o, thus affording a bearing on the lower surface of the plate P on each side of the slot o. The upper section of the block X is fitted to move 60 backward and forward in the slot o, with the upper surface thereof against the lower surface of the head d. The block X is also provided with a suitable aperture for the reception of the lower end of the bolt T, which is 65 inserted from above through the head d of the head-block H. The bolt T is enlarged at its upper end and provided with the recess c, in which the lower part of the bar B rests, and in which it moves when the bolt T is advanced. The lower part of the enlarged portion of said bolt rests upon the upper surface 70 of the head d.

p is a plate, the sleeve v of which is attached to the front side of the evener, and is 75 held in place in the clevis M by the bolt R, which passes through the sleeve v. The lower member n of the clevis M is fitted to and designed to move back and forth in the slot o. The upper member of the clevis M is 80 provided with lugs l l l, between which are the corresponding recesses r r. The upper end of the bolt is forked and provided with a recess corresponding with the recess c of the bolt T. The clevis M is held in place by 85 the bar B and the plate P, the lower member thereof resting in the slot o and the bar B resting in the recess in the bolt R and the recesses r r between the lugs l l l, said recesses forming a track in which the lower 90 edge of the bar B may move when the clevis M is advanced. The bar B is attached to the 95

casings C and D by means of the lugs *t t* and bolts *i i*. When the coil-spring S is in position, the forward end thereof is securely held in place by the casing C, which forms a chamber therefor, while the rear end thereof is against the forward face of the head *d* of the head-block H, with the shank *k* extending forward into the coil of the said spring. The head-block H is held firmly in place by the bolt T and block X, the slot *o* allowing of forward and backward movement and the bar B and plate P preventing lateral movement. Upon applying forward draft to the evener E the face thereof, provided with the plate *p*, is forced against the convex face of the head *d* of the head-block H, and the forward face of the head *d* is at the same time forced against the rear end of the coil-spring S, compressing the same according to the degree of forward draft, and thus securing the yielding connection desired between the draft and animal and the fixed point of draft upon the wagon or other vehicle.

In the above I have confined myself to the spring-draft feature and will now proceed to describe its application as a tongue-support.

It will be observed that the casing D performs no function in the spring-draft feature of my invention, except that it furnishes a point for the support and fastening of the bar B and constitutes a buffer to receive the backward shock of the evener E. For the purposes of a tongue-support the casing D furnishes a chamber for the compression of the coil-spring A. Said chamber is provided in each of its sides with longitudinal slots *a*, in which the bolt *b* of the clevis V moves and presses against the forward end of the coil-spring A, compressing the same when forward pressure is applied to the tongue of the vehicle.

U is a clevis, one end of which is held by the chain N, said chain being attached at its opposite end to the bolster or other fixed part 45 of the wagon or vehicle. It will thus be seen

that a simple and effective device for the support of the tongue without in any manner interfering with the evener and its fastenings to the tongue of the wagon is afforded.

I claim—

1. In a draft - equalizer, the combination, with the tongue of a vehicle, of the plate P, secured thereto and provided with the longitudinal slot *o*, the casings C and D, made integral with said plate, the bar B, connecting said casings, the evener E, provided with the plate *p*, the bolt R, having an enlarged slotted head embracing the bar B, the head-block H, provided with the head *d* and the shank *k*, the bolt T, having an enlarged slotted head 55 embracing the bar B, and the coiled spring S, located between the head *d* and the front end of the casing C, substantially as specified.

2. In a combined draft-equalizer and tongue-support, the combination, with the tongue of a vehicle, of the plate P, secured thereto and provided with the longitudinal slot *o*, the casings C D, made integral with said plate, the bar B, connecting said casings, the evener E, provided with the plate *p*, the bolt R, having the enlarged slotted head embracing the bar B, the head-block H, provided with the head *d* and the shank *k*, the bolt T, having an enlarged slotted head 60 embracing the bar B, the coiled spring S, located between the head *d* and the front end of the casing C, substantially as specified.

In witness whereof I have hereunto subscribed my name this 19th day of November, A. D. 1888.

HIRAM BARBER.
